PORTABLE CRANE

Robert G. Le Tourneau, Peoria, Ill., assignor to
 R. G. Le Tourneau, Inc., Stockton, Calif., a
 corporation of California

Application August 31, 1936, Serial No. 98,654

4 Claims. (Cl. 212—8)

This invention relates to portable cranes for general utility service on highways, shop or construction yards, and similar areas and particularly represents improvements over the tractor mounted crane shown in my co-pending application for patent, Ser. No. 45,040, filed October 15, 1935, issued on April 27, 1937 as Patent No. 2,078,393.

In the previous construction, the crane was arranged so that only a portion of the weight of the tractor was available as a counter-balance for the load carried by the crane, so that the long tongue on the crane base was necessary to provide leverage sufficient to utilize this fragmentary portion of the tractor weight to the best advantage. This made the crane as a whole so long that it could not be efficiently employed in relatively confined quarters. The previous crane was also arranged so that it was behind the tractor, making it necessary for the operator of the latter (and who also controls the crane hoist and boom lines) to twist about in his seat on the tractor to see what he was doing.

The principal objects of the present invention are to avoid the above objectionable features by arranging the crane so that it is ahead of and pushed by the tractor while at the same time enabling the crane to be easily steered or turned with the tractor as a unit; and by mounting the crane on the tractor so that the entire weight of the latter serves as a load counter-balance, thereby making it possible to shorten the base of the crane considerably and provide a correspondingly compact unit.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of my improved crane as mounted on a tractor.

Figure 2 is a top plan view of the same, with the operating cables removed.

Referring now more particularly to the characters of reference on the drawings, the crane comprises a base frame in the form of side beams 1 rigidly connected at their forward ends by a cross beam 2. The beams 1 slope down to their rear end and at said end are provided with bearing boxes 3 to engage trunnions 4. These trunnions are mounted on and project laterally from saddles or brackets 5 secured on the side frames 6 of the track units of a tractor 7 in such a position on the same as to be substantially central of the longitudinal distribution of weight of the 5 tractor.

Bosses 8 project rearwardly from the cross beam 2 adjacent its ends and support the kingpins of swivel forwardly angled forks 9 in which caster wheels 10 are mounted. The base is thus capable 10 of swivel movement relative to the tractor in a vertical plane but is rigid with the tractor in a horizontal plane, so that as the tractor is turned to one side or the other, the crane base will turn likewise. As the tractor thus turns the caster 15 wheels swing also, so that no interference with the desired ease of steering of the tractor is had.

The crane boom is substantially of the same form as shown in said co-pending application and includes upwardly converging side arms 11 having a forward overhang 12 at their forward upper end and from which the load engaging hook 13 or the like is supported by a conventional hoist cable arrangement 14. The cable 14 initially extends over a guide pulley 15 from one drum of a suitable double drum power hoist unit H mounted at the back of the tractor as is now common practice. The boom control cable 16 extends from the other drum of the hoist, to and between a sheave block 17 mounted as a unit with the pulley 15 and a sheave block 18 mounted on the boom at 20 the top.

The block 17 is mounted above the tractor substantially midway of the length and centrally of the width thereof on an auxiliary arch frame 19 which straddles the tractor and is rigid with the rear ends of the beams 1, being braced from the cross beam 2 by a central brace bar 20 extending from said auxiliary frame under the block 17 and over the front of the tractor to the 25 cross beam. The auxiliary frame is sufficiently high so that the operator of the tractor has unobstructed view ahead from under the same.

The boom arms 11 are pivoted at their lower ends on ears 21 upstanding from the cross beam 2 adjacent its ends and substantially in a common vertical plane with the axis of the wheels 10 when the latter are disposed in normally trailing relation. In this manner the load is carried directly over the wheel and also is counter-balanced by 30 the entire weight of the tractor. Relatively large loads even with a considerable forward angling of the boom may thus be handled without any tendency to tip the tractor.

As in the previous structure the boom is adapted 35

to be raised to a vertical position so that the load may be handled very close to the front end of the base. To prevent backward tipping of the boom from such position, I provide transversely spaced pads 22 adapted to rest on the auxiliary cross beam 23 of the base when the boom is vertical. The pads are rigidly connected to the boom arms, by arms 24 diverging from the pads.

From the above description it will be seen that while the crane is rigid with the tractor when operatively connected thereto, so that said tractor and crane base may be steered as a unit, it is but the work of a few minutes at most to remove the crane from association with the tractor when the use of said crane is not desired. All that it is necessary to do to effect this removal is to disconnect the bearing boxes 3 from the trunnions 4 and back the tractor away from the crane. The trunnion supporting brackets remain permanently on the tractor since they do not of course interfere with any of the normal operations thereof, and are the only parts of the structure which are permanently attached to the tractor.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A portable crane comprising a base having side beams adapted to extend on opposite sides of a tractor from in front thereof, means to swivelly mount the rear end of the beams on the tractor, for relative movement in a vertical plane, transversely spaced swivel caster wheels supporting the base ahead of the tractor and having the axis of the swivel horizontally offset from the axis of the wheels, and a boom mounted on and upstanding from the base ahead of the tractor. 5

2. A portable crane attachment for a tractor comprising a base frame which includes side beams spaced to straddle the tractor and a cross beam rigidly connecting the side beams at their outer ends, means to removably mount the side beams at their opposite ends on the side frames of the tractor intermediate the ends of said side frames for swivel movement in a vertical plane, a sheave-supporting auxiliary frame rigid with and upstanding from the side beams adjacent 15 said opposite ends thereof and adapted to extend above and across the tractor, a boom mounted on the base frame adjacent the outer end thereof, and wheels supporting the base frame at said outer end thereof. 20

3. A structure as in claim 2, in which the side beam mounting means comprises brackets adapted to be secured on the side frames of the tractor and trunnions on the brackets turnably 25 engaging the side beams. 30

4. A structure as in claim 2, with a central diagonal brace bar extending between and rigid with the cross beam and the auxiliary frame at the top thereof. 35

ROBERT G. LE TOURNEAU.
